Primary Examiner — Robert Delehaney(74) *Attorney, Agent, or Firm* — Stetina Brunda Garred & Brucker(57) **CLAIM**

The ornamental design for a pedicure spa platform, as shown and described.

DESCRIPTION

FIG. 1 is a front perspective view of the pedicure spa platform of the present invention showing my new design with the dotted lines depicting solely environmental structure and forming no part of the claimed design;

FIG. 2 is a side elevational view thereof;

FIG. 3 is a top plan view thereof;

FIG. 4 is a front end view thereof;

FIG. 5 is a rear end view thereof; and,

FIG. 6 is a bottom plan view thereof.

The broken lines showing environment are for the purpose of illustration and form no part of the claimed design.
